Primary Examiner — Kevin Rudzinski

(74) Attorney, Agent, or Firm — David M. Driscoll, Esq.

(57) **CLAIM**

The ornamental design for a protective dome, as shown and described.

DESCRIPTION

FIG. 1 is a perspective view of a protective dome;
 FIG. 2 is a top plan view thereof;
 FIG. 3 is a bottom plan view thereof;
 FIG. 4 is a left side elevational view, the right side being a mirror image thereof;
 FIG. 5 is a front elevational view thereof;
 FIG. 6 is a rear elevational view thereof; and,
 FIG. 7 is a perspective view thereof showing the protective dome in use.
 The broken lines illustrating a lighting fixture in FIG. 7 is shown to illustrate environmental structure and form no part of the claimed design.

1 Claim, 4 Drawing Sheets# US D680,680 S
